ELECTRIC SWITCH

Application filed June 20, 1928. Serial No. 286,974.

This invention relates to electric switches and while features of the invention may be applied in the construction of switches of any type, the invention is expected to be especially useful when applied to a wall switch, such as is employed in dwellings for closing the circuit through chandeliers or wall lights. Wall switches practically all embody in their construction a spring which holds the switch both in its closed and open position, and such switches are usually of the "snap" type, that is to say, they are so constructed that by moving the hand controlled part past a certain point, the spring will then operate to continue the movement and "snap" the switch over to the opposite position. One of the disadvantages of this type of switch is that it appears to be necessary to provide a spring of considerable strength and hence such a switch makes considerable noise when it is actuated. This noise may awake persons sleeping in an apartment adjoining one in which the switch is operated late at night. One of the disadvantages of a switch of this type having a strong spring, is that it requires considerable force to operate the hand controlled member, switch lever or push button and when the spring snaps the switch over, a considerable force and shock is imparted to the fastenings which support the switch in the wall; the result of this is that frequently such switches eventually loosen the plaster in their vicinity.

The general object of this invention is to provide a switch of very simple construction especially adapted for use as a wall switch and which will be substantially noiseless in its operation; also to provide a switch of this type which will operate without the use of a spring and which can be operated by the application of a very slight force to the actuating lever or push button.

One of the objects of the invention is to produce a wall switch which can be operated with so little force that it need not be securely fastened to the wall lath, but which can, if desired, merely be set in the plaster of the wall.

A further object of the invention is to provide a switch of this type which is especially

adapted for carrying a liquid, such as oil, immersing the contacts, and thereby avoiding sparking and the injurious effects consequent thereto.

Further objects of the invention will appear hereinafter. 55

The invention consists of the novel parts and combination of parts to be described hereinafter, all of which contribute to produce an efficient electric switch. 60

A preferred embodiment of the invention is described in the following specification, while the broad scope of the invention is pointed out in the appended claims. 65

The accompanying drawings illustrate the invention. 70

Figure 1 is a side elevation of an electric switch constructed in accordance with the provisions of this invention.

Figure 2 is a horizontal section on the irregular line indicated by 2-2, Figure 1. 75

Figure 3 is a section on line 3-3 of Figure 1.

Before proceeding to a detailed description of the switch, it will facilitate the disclosure of the invention to state that this switch is constructed in such a way that it is movable with substantially equal freedom in either direction, that is to say, in the direction to close the switch or to open it. This is preferably accomplished by avoiding the use of a spring and by constructing the switch in such a way as to avoid the employment of the "snap" principle commonly used in switches of this type. Any simple construction can be employed for the hand operated member that controls the switch and any suitable means may be employed for imparting this movement to the switch member that actually closes the switch through the agency of the contacts within the switch. 85 80 90

According to my invention, I provide a switch casing and a wall plate. The switch casing performs the function of a frame for carrying the movable switch member which is controlled by the hand operated part of the switch. The movable switch member is preferably rotatable and operates when moved in one direction to open the switch, and in the other direction to close the switch. 100

A connection is provided from the hand actuated part or parts to this switch member to give it this simple movement, and all of the parts cooperate in their movements so that they move freely with equal freedom in either direction. Their inertia of rest holds the switch as left.

The switch is devoid of any spring or any part performing the function of a spring.

19 I shall now describe a simple embodiment of the invention.

Referring to the drawing the electric switch comprises a rotatably mounted shaft 6 to which is fixed in a suitable manner an electric insulation member 7. Partly surrounding the member 7 is an electric contact 8 which, thus, is rotatably mounted. The contact 8 constitutes the segment of a ring and between the ends of said segment protrudes a portion 9 of the member 7, said portion 9 constituting an insulating section having substantially the same radius as the outer face of the contact 8.

The shaft 6 rotates in bearings 10, 11 which, in this instance, are formed in lower and upper heads 12, 13, respectively, of a cylindrical container or housing that is indicated in general by the character 14. The heads 12, 13 may be sealed in place so as to make the container 14 oil tight and, if desired, oil, not shown, may be placed in the container.

The shaft 6 projects above the head 13 and is provided on its upper end with an arm 15. Pivoted at 16 to the outer end of the arm 15 is a non-extensible link 17 which in turn is pivoted at 18 to a lever 19. By non-extensible I mean that the link 17 is not a spring. My switch is devoid of a spring between the hand-actuated member and the switch. The fulcrum of the lever 19 is indicated at 20 and is in the form of a pin which is supported at its opposite ends in the sides of a substantially U-shaped bracket 21. The end portions 45 of the bracket 21 are outwardly flared as indicated at 22, so as to receive between said flared ends the container 14. To the flared ends 22 are welded, or otherwise secured, semi-circular clamping members 23 which fit 50 the periphery of the container 14.

The clamping members 23 are provided with ears 24 that project beyond the periphery of the container 14 and a bolt 25 passes through the ears 24 for the purpose of holding the clamping members 23 toward one another, thus to securely support the container 14.

The lever 19 is operated, in this instance, 60 by a pair of push buttons, an upper button 26 and a lower button 27. The button 26 is secured to the outer end of an arm 28 which is pivoted at 29 to the lever 19 at a point between the pivot 18 and fulcrum 20. The button 27 is secured to an arm 30 which is

pivoted at 31 to the lever 19 at a point below the fulcrum 20. The pivots 29, 31 are approximately equidistant from the fulcrum 20 so that the lever 19 will be swung the same distance in opposite directions by movement of the buttons 26, 27 through like distances. The arm 15, 15 always extends at some angle in relation to the link 17 so as to avoid dead centers, thus making it possible by alternately pushing the buttons 26, 27 to oscillate the 75 shaft 6 and the electric contact 8.

Arranged diametrically opposite one another and adapted to engage the contact 8, when said contact is in the position shown in Fig. 2, are stationarily mounted electric contacts 32, 33 of arcuate shape. When the contacts 8, 32, 33 are engaged, the switch is on or closed and in this position the button 26 is out and the other button 27 is in. Therefore, for purposes of description, it may be assumed that the button 26 is the "off" button, and the button 27 is the "on" button. To open the switch so as to break the electric circuit the button 26 will be depressed, thus rotating the shaft 6 clockwise in Fig. 2 to thereby cause 90 the contact 8 to rotate out of engagement with the contact 33.

In this instance, the buttons 26, 27 pass through orifices 34, 35 in a plate 36 which plate is adapted to be secured to any suitable support, not shown. The bracket 21 is riveted, or otherwise secured to the plate 36.

The contacts 32, 33 are provided at their upper ends with U-shaped fastening clips 37 which embrace the upper end of the container 14. Binding posts 38 pass through the clips 37 and through the wall of the container 14, the heads 39 of the binding post screws being inside of the container. The wires of the circuit that is to be controlled by the switch 105 will be secured to the binding posts 38.

Briefly stated, the invention operates as follows: Assuming that the parts are in the circuit closing position, as in Figs. 1 and 2 of the drawings, to turn the switch off, the button 26 will be depressed, thus swinging the upper end of the lever 19 to the left in Fig. 1, thereby rotating the shaft 6 clockwise. This causes the contact 8 to rotate out of engagement with the contact 33, thereby interrupting 110 the flow of current between the contacts 32, 33. At the same time the lower end of the lever 19 is caused to swing to the right in Fig. 1, thus pushing out the button 27.

To then close the switch, the operator will 120 depress the button 27 so as to swing the upper end of the lever 19 to the right in Fig. 1, thereby turning the contact 8 counter-clockwise to the position shown in Fig. 2 so as to engage not only the contact 32 but also the contact 125 33, thereby enabling electric current to flow between the contacts 32, 33. When the upper end of the lever 19 is swung to the right, it pushes out the button 26.

From the foregoing it will be seen that the 130

invention is very simple and positive in action and that I avoid the use of a spring. The contacts 32, 33 are of spring brass and are under a slight tension so as to press against the contact 8.

5 What I claim is:

1. In a noiseless electric wall-switch for closing an electric circuit, the combination of a wall-plate, a switch-casing, a movable switch-member for opening and closing the circuit, hand actuated means supported on the wall-plate, and non-extensible means connecting the same with the switch-member to operate it, said parts being freely movable from their position of rest in a direction to close or open the switch and operating to hold the switch closed or open by reason of the inertia of rest of the parts in the position in which they are left.

20 2. A noiseless electric wall-switch having in combination, a wall-plate, a switch-casing having a pair of separated contacts, a movable switch-member carried by the casing, cooperating with the contacts to open or close a circuit through the same, hand actuated means supported on the wall-plate, and non-extensible means connecting the last named means with the switch-member, freely movable in a direction to close or open 30 the switch, said parts cooperating to hold the switch closed or open through the inertia of rest of the parts in the position in which they are left.

3. A noiseless electric wall-switch having in combination, a wall-plate, a switch-casing, a pair of separated contacts, a movable switch-member carried by the casing cooperating with the contacts to open or close a circuit through the same, hand actuated 40 means supported on the wall-plate, and non-extensible means connecting the last named means with the switch-member freely movable with equal freedom in the direction to close the switch or to open the switch, said 45 parts cooperating to maintain the switch open or closed through the inertia of rest of the parts in the position in which they are left.

4. A noiseless electric wall-switch for closing an electric circuit, having in combination, a wall-plate, a switch-casing having a pair of separated contacts, a rotatable switch-member carried by the casing cooperating with the contacts to open or close the 55 circuit, said rotatable switch-member being movable with equal freedom in a direction to close the switch or to open the same, hand actuated means supported on the wall-plate, non-extensible means, that is to say, means 60 devoid of a spring, connecting the same with the switch-member, said hand actuated means being freely movable with equal freedom in the direction to close the switch or to open the switch, and all of said parts 65 cooperating to hold the switch closed or open

through the inertia of rest of the parts in the position in which they are left.

5. A noiseless electric wall-switch for closing an electric circuit, having in combination, a wall-plate, a switch-casing carried by 70 the wall-plate and having a pair of separated contacts, a rotatable switch-member mounted to rotate on an axis substantially parallel with the wall plate, carried by the casing cooperating with the contacts to open 75 or close the circuit, a pivotally supported lever mounted back of the wall plate to swing in a plane substantially at right angles to the plane of the wall-plate, a connection from the lever to the rotatable 80 switch-member to move the same to open or close the circuit, a push-button guided on the wall plate for moving the lever in one direction, another push button guided on the wall-plate to move the lever in the other 85 direction, said parts being freely movable with equal freedom in either direction, and cooperating to hold the switch open or closed through the inertia of rest of the parts in the position in which they are left. 90

6. An electric switch comprising a rotatably mounted shaft, an arm fixed to said shaft, a link pivotally connected to said arm, a lever pivotally connected to the link, push buttons connected with the lever on opposite 95 sides of the fulcrum of the lever, a segmental electric contact mounted on and insulated from the shaft, and electric contacts mounted at opposite sides of the shaft in position to both engage the first mentioned contact when the shaft is turned in one direction, one of the second mentioned contacts being out of engagement with the first mentioned contact when the shaft is turned through a predetermined number of degrees 100 in the opposite direction. 105

7. An electric switch comprising a container provided with heads closing its opposite ends, a shaft journaled in said heads and projecting outside of the container, an arm fixed to the projecting end of said shaft, a means to oscillate the arm, a segmental electric contact mounted on and insulated from the shaft within the container, and electric contacts mounted on opposite sides of the container in position to both engage the first mentioned contact when the shaft is turned in one direction, one of the second mentioned contacts being out of engagement with the first mentioned contact when the shaft is turned through a predetermined number of degrees in the opposite direction. 110 115 120
